UNITED STATES PATENT OFFICE.

EDWARD E. FERGUSON, OF PORTSMOUTH, VIRGINIA, ASSIGNOR OF ONE-HALF TO
C. VAN FLEMING, OF NORFOLK, VIRGINIA.

COMBINED FIRE-ALARM BOX AND HYDRANT.

1,391,622.

Specification of Letters Patent. Patented Sept. 20, 1921.

Application filed November 18, 1919. Serial No. 338,902.

To all whom it may concern:

Be it known that I, EDWARD E. FERGUSON, a citizen of the United States, residing at Portsmouth, in the county of Norfolk and 5 State of Virginia, have invented certain new and useful Improvements in Combined Fire-Alarm Boxes and Hydrants; and I do hereby declare the following to be a full, clear, and exact description of the invention, such 10 as will enable others skilled in the art to which it appertains to make and use the same.

The present invention relates to improvements in combined fire alarm box and hydrant, and consists in certain improvements 15 over the device shown in my prior Patent No. 1,215,263, granted February 6, 1917.

It is an object of the present improvement that the fire alarm box and valve 20 structure of the hydrant are inclosed within a casing which is closed against tampering and which avoids the accidental or malicious opening of the hydrant valve without turning in the alarm.

Another object of the present invention resides in providing an improved combined 25 fire alarm box and hydrant in which the structure will be compact and inexpensive and being capable of installation in connection with existing mechanism.

In the accompanying drawings forming a 30 part of this application, and in which similar reference symbols indicate corresponding parts in the several views:

Figure 1 is an elevational view of a combined fire alarm box and hydrant constructed according to my present invention;

Fig. 2 is an enlarged elevational view of the same with the cover in the open position, 40 showing the interior of the casing;

Fig. 3 is a vertical sectional view through the casing, showing the parts in the normal positions;

Fig. 4 is a similar view showing the parts 45 in position after the alarm has been turned in and the hydrant valve opened;

Fig. 5 is a fragmentary elevational view, with parts shown in section, of the cable release; and

Fig. 6 is a similar view showing certain 50 parts in section.

Referring more particularly to the drawings, 1 designates a water service pipe which is connected with the main, from which it receives its supply. This service pipe passes 55 through a casing 2 and issues from the opposite side thereof, where it is in connection with one end of a hose 3 carried upon a rack 4 in the usual manner and having a nozzle 5.

As clearly shown in Fig. 3, the nozzle 5 is 60 made with a projection 6 adapted to enter through an opening 7 in the front wall of the casing, and this projection 6, which is notched on its under side, as clearly shown 65 serves the two-fold function of supporting the nozzle 5 and also of holding the alarm mechanism which is contained in the fire alarm box 8, also carried within the casing 2, in an initial inoperative position. This is accomplished by the projection 6 being 70 received on insulated end 9 on the lower portion of the spring lever 10 which swings about the center 11, and so disposed as to fall from the position shown in Fig. 3 to that shown in Fig. 4 when the nozzle 5 is 75 removed from the casing. The falling of the lever 10 is adapted, in the well known manner, to set into operation the alarm mechanism within the box 8.

The spring lever 10 carries an arm 12 to 80 which is connected a chain 13 having a handle 14 on its lower end which is intended to be grasped when the parts are in the position shown in Fig. 4 and drawn down for the purpose of elevating the lever 10 to its initial position prior to returning the projection 6 on the nozzle into its place within the opening 7 in the casing.

The spring lever 10 carries a stop 15 which is normally intended to be engaged by 90 an arm 16 carried by a lever 17 which is fulcrumed within the casing 2, and normally has its free end engaged with a valve lever 18. When the spring lever 10 falls, however, the stop 15 is withdrawn from the arm 16, 95 which allows the lever 17 to fall in which it is assisted by a spring 55 out of engagement with the valve lever 18 and allow such latter lever to be rocked about its pivotal center 19 as by mechanism hereinafter described.

The valve lever 18 is of the curved con-

struction, best shown in Figs. 3 and 4, in order to enable it to embrace the service pipe within the casing 2. This lever 18 is intended to operate any suitable type of valve 20 within the casing 21, and when the lever is in the lower position shown in Fig. 3 the valve is closed, preventing the escape of water through the hose and nozzle 5; while the valve 20 is opened by the swinging of the lever up into the position shown in Fig. 4.

A handle 22 is connected to the valve lever 18 in order to draw the lever back to the initial position after each actuation. The valve lever carries a segment 23 having an elongated slot 24 in which is engaged one end of a rod 25, which is suitably bent or offset so as to pass up and connect to a vertically reciprocating latch 26 operating in a casing 27 and normally urged upward by a coil spring 28. The latch engages a shoulder 29 on the cover 30 of the casing 2, which cover is hinged at its lower end adjacent the base of the casing, as indicated at 31.

25 Springs 32 are carried by the side edges of the casing 2 and are arranged to be compressed by the cover 30 when closed, with the result that when the latch 26 is withdrawn from the shoulder 29 the springs 32 30 come into play and rock the cover 30 back, so that it will fall by gravity to the open position.

Referring more particularly to Figs. 5 and 6, the valve lever 18 is provided with a finger 33 pivoted as indicated at 34 and carrying a pin 35 which is connected to a tooth 36. A spring 37 normally acts to project the tooth and to keep the same in engagement with the notched part 38 of a tip 39 on a flexible cable 40 which fits through the opening made for the purpose in the upper end of the valve lever 18.

The finger 33 is arranged to strike a part of the casing 2, or other adjacent part, when such lever is in the raised position shown in Fig. 4, and when the finger strikes the casing or other part, it is rocked about the pivot 34 and causes the plunger 36 to be retracted out of the path of the notched part 38, thus releasing the tip 39 and allowing the cable 40 to become free of said valve lever 18. This construction is more particularly described and claimed in my prior patent aforesaid.

55 The cable 40 passes out through an opening made in the casing and between a pair of swivel pulleys or a swivel ring 41, and as shown in Fig. 1 has its opposite end provided with a ring or clamp 42 which 60 braces the hose 3 at a suitable point; the idea being that when the hose is all off the rack or reel, and straightened out ready for action, a slight pull on the hose will pull upon the cable 40, thus causing the valve lever 18 to be swung up and the valve 20

opened, the alarm being turned in at the same time by the removal of the nozzle 5 from the casing.

The drain pipe 43 is shown as connected to the service pipe and as being provided with a valve 44. This valve 44 is preferably so arranged that when the main valve 20 is closed the valve 44 will be opened, but when the main valve 20 is open the pressure will act on the valve 44 and cause the same to close. The drain valve is the usual form of check valve opened by pressure and seating when pressure is relieved, and *per se* forms no part of the present invention.

An arm 50 is fulcrumed on a pivot 51 carried by the valve lever 18 and is normally urged by a coil spring 52 to swing about the pivot 51 in a counterclockwise direction. An extension 53 of the arm 50 is arranged to be engaged by a projection 54 of the pin 39, 80 so that when the pin is in place the projection 54 will engage the extension 53 and hold the arm 50 in the position shown in Fig. 3. When, however, the pin 39 is released, the removal of the projection 54 will 90 allow the spring 52 to swing the arm 50 about the pivot 51 so that such arm 50 will assume substantially the position shown in Fig. 4, where it will prevent the closing of the cover 30 prior to re-inserting the pin 39 95 in the valve lever 18. By this arrangement it is assured that the cover 30 will not become latched without first connecting the cable 40 to the valve lever 18, as the same would not be set for action were this connection not 100 made. A leaf spring 55 bears on the arm 17, causing it to drop promptly, releasing the lever 18, when the stop 15 is withdrawn from the arm 16.

Clips 56 are shown as affixed to the front 105 wall of the casing for assisting in supporting the nozzle 5 and also for assisting in the removal of the nozzle. A swinging of the nozzle to the right or left will cause it to become disengaged from the box.

In operation the parts are normally in the position shown in Fig. 3, and when the nozzle 5 is removed, the lever 10 will drop and turn in the alarm. At the same time the hose 3 will be removed from the rack 4, and as the same is straightened out ready for action a slight pull will draw the cable 40, thus causing the swinging of the valve lever 18 accompanied by the opening of the valve 20 and the withdrawal of the latch 26, 115 resulting in the opening of the cover 30. The cable 40 will also be released so as not to cause any possible kinking of the hose which would interfere with the flow of the water.

When the parts are to be restored to initial 125 position the handle 22 is grasped and the valve lever 18 returned to the lowered position, the tip 39 being threaded through the swivel pulleys or swivel ring 41 and again engaged with the valve lever 18 after the hose 130

has been put back in place on the rack 4 and the spring lever 10 is restored to the upper position after which the nozzle is again put in place. The cover 30 may then be again 5 raised and will be automatically locked by the latch 26. The apparatus can in this condition not be tampered with unless the nozzle 5 is removed which turns in the alarm.

It is obvious that those skilled in the art 10 may vary the details of construction and arrangements of parts without departing from the spirit of my invention, and therefore I do not wish to be limited to such features except as may be required by the claims.

15 I claim:

1. In combination, a service pipe, a valve therein, actuating means for the valve, a hose connected to the service pipe, a connection between the hose and actuating means 20 for acting to open the valve, a fire alarm apparatus adjacent said actuating means, a nozzle for the hose normally acting to hold the alarm apparatus in an initial potential position, and means held in place by the 25 alarm apparatus for preventing the movement of the actuating means, substantially as described.

2. In combination, a service pipe, valve means therein, actuating means for the valve 30 means, a hose connected to said pipe, a connection between the hose and actuating means for acting to open the valve means, a fire alarm apparatus near said actuating means, a nozzle for the hose normally acting 35 to hold the alarm apparatus in an initial potential position, and means fitted to swing between said apparatus and actuating means for normally rendering the latter inoperative, substantially as described.

40 3. In combination, a service pipe, valve means therein, actuating means for the valve means, a hose connected to said pipe, a connection between the hose and actuating means for acting to open the valve means, 45 a fire alarm apparatus near said actuating means, a nozzle for the hose normally acting to hold said alarm apparatus in an initial potential position, and a lever fulcrumed between said actuating means and alarm apparatus and normally engaging both but 50 released from engagement with the actuating means when the alarm apparatus is actuated, substantially as described.

4. In combination, a service pipe, valve 55 means therein, actuating means for the valve means, a hose connected to said pipe, a connection between the hose and actuating means for acting to open the valve means, a fire alarm apparatus near the actuating 60 means, a nozzle for the hose normally acting to hold said alarm apparatus in an initial potential position, a lever pivoted between the actuating means and alarm apparatus adapted to normally engage the former and 65 having an arm engageable with the latter,

and spring means for disengaging the lever from the actuating means when the arm is released, substantially as described.

5. In combination, a service pipe, a valve 70 therein, actuating means for the valve, a fire alarm apparatus situated close to the valve, a hose connecting to the service pipe, a nozzle for the hose adapted to hold the alarm mechanism in an initial potential position, a casing inclosing said valve and 75 alarm mechanism, a cover for the casing, spring means normally tending to open the cover, latch means within the casing normally holding the cover closed, and means to automatically open the cover when said 80 actuating means for the valve is moved to open the valve, substantially as described.

6. In combination, a service pipe, a valve 85 therein, a hose connected to the service pipe, an alarm mechanism situated beside the valve, a nozzle for the hose acting normally to maintain said alarm mechanism in an initial potential position, a casing inclosing said service pipe, valve and alarm mechanism, a normally openable cover for the casing, 90 latch means within the casing and inaccessible from the exterior for normally holding said cover closed, means connected between the hose and the valve actuating means for shifting the latter to open the 95 valve, and latch releasing means associated with said actuating means, substantially as described.

7. In combination, a casing, a cover hinged thereto, and extending about one side and 100 a portion of the upper part of the casing, spring means compressible when the cover is closed and acting to urge the cover to an open position, latch means within the casing and inaccessible from the exterior for normally holding the cover closed in opposition to the influence of said spring means, a service pipe passing through said casing, a valve included in the pipe and situated 105 within the casing, a lever for opening and closing said valve, a connection between said lever and said latch means, an alarm mechanism in the casing, a hose connected to the service pipe and supported at an elevation, a nozzle for the hose having a part 110 adapted to project within the casing and to both support the nozzle and hold the alarm mechanism in an initial potential position, and a connection between said hose and said lever, substantially as described. 115

8. In combination, a casing a cover hinged thereto, spring means normally acting on said cover and tending to open the same, a latch within the casing normally holding said cover closed, a service pipe passing 120 through the casing, a valve included in the service pipe within said casing, a lever in the casing connected to actuate said valve, a slotted segment, movable with said lever, a rod connected to said latch and having a 125 130

part playing in the slot in said segment, an alarm mechanism in the casing, a hose connected to the service pipe and normally supported at an elevation a nozzle for the hose having a projection adapted to extend within the casing and both support the nozzle and hold the alarm mechanism in a potential

position, a flexible and releasable connection between the hose and said lever and means between said alarm mechanism and lever for holding the latter against operation before the alarm is released, substantially as described.

EDWARD E. FERGUSON.
